UNITED STATES PATENT OFFICE

170,862

TIRE

Earle W. Hawkinson, Minneapolis, Minn., assignor to Paul E. Hawkinson Company, Minneapolis, Minn., a corporation of Minnesota

Application July 27, 1953, Serial No. 26,140

Term of patent 14 years

(Cl. D90—20)

To all whom it may concern:

Be it known that I, Earle W. Hawkinson, a citizen of the United States, residing at Minneapolis, county of Hennepin, and State of Minnesota, have invented a new, original, and ornamental Design for a Tire, of which the following is a specification, reference being had to the accompanying drawing, forming a part thereof.

Fig. 1 is a view in perspective of a tire, showing my new design; and

Fig. 2 is a fragmentary view in transverse section, taken on the line 2—2 of Fig. 1.

The dominant features of my design reside in those portions shown in full lines.

I claim:

The ornamental design for a tire, as shown and described.

EARLE W. HAWKINSON.
